UNITED STATES PATENT OFFICE.

CLARKSON W. MACY, OF CONVERSE, INDIANA.

CLOSET ATTACHMENT.

1,218,882.

Specification of Letters Patent. Patented Mar. 13, 1917.

Application filed January 11, 1917. Serial No. 141,863.

To all whom it may concern:

Be it known that I, CLARKSON W. MACY, a citizen of the United States, residing at Converse, in the county of Miami and State 5 of Indiana, have invented a new and useful Closet Attachment, of which the following is a specification.

The present invention relates to a closet attachment or deodorizer, and aims to provide 10 a novel and improved device of that character for spraying a deodorant into the bowl, thereby providing for sanitation.

It is the object of the invention to provide 15 a device of the character indicated which can be readily applied to various bowls, and which is simple and inexpensive in construction, and which will perform its office in a thoroughly efficient manner.

With the foregoing and other objects in 20 view which will appear as the description proceeds, the invention resides in the combination and arrangement of parts and in the details of construction hereinafter described and claimed, it being understood 25 that changes in the precise embodiment of the invention herein disclosed can be made within the scope of what is claimed without departing from the spirit of the invention.

The invention is illustrated in the accompanying drawing, wherein:

Figure 1 is a plan view of the device, portions being broken away.

Fig. 2 is an enlarged section taken on the line 2—2 of Fig. 1.

In carrying out the invention, there is 35 provided an open oval-shaped or annular body or member 1 composed of wood or other suitable material and adapted to seat upon the rim of any standard bowl 2. A ring 3 is secured to the inner edge of the member 1 and provides a depending apron 40 or flange 4 to hang within the rim of the bowl, for holding the member 1 in place thereon. A ring 5 is secured to the outer 45 edge of the member 1, and a cup 6 for containing an atomizer is suitably attached, as at 7, to the ring 5, preferably at one side thereof, or at a point where it is out of the way.

Any suitable atomizer is used for spraying 50 the deodorant, the atomizer illustrated embodying the bottle or receptacle 8 held by the cup 6, and the spray nozzle 9 which is

so placed as to extend across the member 1 to deliver the spray into the bowl.

In order to force air through the atomizer, 55 there is provided a continuous or endless deflatable tube 10 of rubber or other suitable material and of the same general shape as the member 1. The tube 10 has flat top and bottom surfaces and bulged sides, the bottom surface of the tube being cemented or otherwise secured upon the member 1 to prevent the displacement of the parts. The tube 10 has an outward nipple 11 near the atomizer, 60 to which a flexible tube 12 is connected, said tube 12 being also connected to the atomizer for conducting the air from the deflatable tube 10 into the bottle 8 from which it is discharged through the nozzle 9 in the form 65 of a spray. The tube 10 is provided at a suitable point with an air inlet nipple 13 provided with a check valve 14, allowing the air to enter the tube 10 through the nipple 13 but preventing the escape of air through 70 said nipple, thereby constraining the air to be discharged through the tube 12 and atomizer.

A seat 15 of wood or other suitable material and of the same general shape as the member 1 and tube 10 is seated upon the tube 10 and is preferably cemented to the upper flat surface of said tube. A depending annular apron 16 is secured to the seat 13 adjacent to its inner edge and protects 80 the tube 10. The apron 16 also overlaps the inner edge of the member 1 to guide the seat 15 for up and down movement, the apron 16 having a vertical slot 17 for accommodating the tip of the nozzle 9, whereby said 85 nozzle can project through the apron 16 when the seat 15 is depressed.

In operation, when the seat 15 is depressed, the tube 10 is deflated, thereby forcing the air through the tube 12 and atomizer, the air in flowing through the atomizer and from the nozzle 9 spraying the deodorant into the bowl. After the flushing 95 action, when the seat 15 is allowed to rise due to the resiliency of the tube 10, the expansion of said tube will suck air into the same through the nipple 13, thereby filling the tube 10 with air for a subsequent operation. The present device, as illustrated, is 100 designed to replace the ordinary seat, although it can be modified, within the scope 105

of what is claimed, for use in connection with ordinary seats.

Having thus described the invention, what is claimed as new is:

5. 1. A closet attachment embodying a deodorant atomizer for spraying the interior of a bowl, and an endless deflatable tube connected to the atomizer for supplying air thereto, and adapted to be supported upon the bowl.
10. 2. A closet attachment embodying a body member to seat on a bowl, a deodorant atomizer for spraying the interior of the bowl, a deflatable member upon said member and connected to the atomizer for supplying air thereto, and a seat upon said deflatable member.
15. 3. A closet attachment embodying a member to seat on the rim of a bowl, a deodorant atomizer for spraying the interior of the

bowl, an endless deflatable tube seated upon said member and connected to the atomizer for supplying air thereto, and a seat mounted upon said tube.

4. A closet attachment embodying a member to seat on the rim of a bowl, a deodorant atomizer for spraying the interior of the bowl, an endless deflatable tube seated upon said member and connected to the atomizer for supplying air thereto, a seat mounted upon said tube, and a depending apron carried by the seat to overlap the inner edge of said member and protect said tube.

In testimony that I claim the foregoing as my own, I have hereto affixed my signature in the presence of two witnesses.

CLARKSON W. MACY.
